DF D 12,713

Design No. 12,713, dated January 31, 1882.

UNITED STATES PATENT OFFICE.

HERMANN ERBS, OF PHILADELPHIA, PENNSYLVANIA.

DESIGN FOR A CARPET.

SPECIFICATION forming part of Design No. 12,713, dated January 31, 1882.

Application filed November 26, 1881. Term of patent 7 years.

To all whom it may concern:

Be it known that I, HERMANN ERBS, a citizen of the United States, residing in the city and county of Philadelphia, State of Pennsylvania, have invented and produced a new and original Design for Carpet, of which the following is a specification, reference being had to the accompanying photographic illustration, forming part thereof.

10 My design consists of a carpet the face whereof is a field with transverse stripes at intervals, and a row of dots in the stripes.

It also consists of the design of the back, having a field with longitudinally-extending stripes of zigzag rows and transverse stripes at intervals.

15 A represents the field of the face of the carpet, having transverse stripes *c* at intervals.

In the stripes is a row of dots, *b*, extending transversely.

20 B represents the fabric of the back of the carpet, having transverse stripes *c* at intervals and longitudinally-extending stripes of zigzag rows *d*. In the stripes *c* are floats *e*.

The design is neat and attractive.

25 I claim—

1. The design for carpet the face whereof has stripes *a*, with rows of dots *b*.
2. The design for carpet the back whereof is a field with transverse stripes *c* at intervals 30 and longitudinally-extending stripes of zigzag rows *d*.

HERMANN ERBS.
